UNITED STATES PATENT OFFICE.

JAMES W. LESLIE, OF CHELSEA, MASSACHUSETTS, ASSIGNOR TO LESLIE MANUFACTURING COMPANY, OF CANTON, MASSACHUSETTS, A CORPORATION OF MAINE.

DESIGN FOR A BLADE FOR SAFETY-RAZORS.

43,082.

Specification for Design.

Patented Oct. 1, 1912.

Application filed May 31, 1911. Serial No. 630,488. Term of patent 14 years.

To all whom it may concern:

Be it known that I, JAMES W. LESLIE, a citizen of the United States, residing at Chelsea, county of Suffolk, State of Massachusetts, have invented a new, original, and ornamental Design for a Blade for Safety-Razors, of which the following is a specification, reference being had to the accompanying drawing, forming part thereof.

The figure is a perspective view of a safety razor blade showing my new design, wherein the characteristic feature is the razor blade

having the gracefully and ornamentally curved ends 4 terminating in two separated prongs or projections at each end having the scalloped upper edge between said projections.

I claim:

The ornamental design for a safety razor blade, as shown and described.

JAMES W. LESLIE.
